ADJUSTABLE TABLE TOP

Bert H. Gibson and Leroy C. Lunsford, Newcastle,
Ind., assignors to The Hoosier Manufacturing
Company, Newcastle, Ind., a corporation of
Indiana

Application October 16, 1939, Serial No. 299,637

5 Claims. (Cl. 311—48)

This invention relates to table tops and particularly to means for shifting a leaf from a stored position into position for top extension and for returning the leaf to the stored position. An important advantage of the invention is that the leaf may be formed in two sections so arranged and mounted that the lifting of one section will substantially, automatically shift the other section into position between the table top ends without further action upon the part of the operator.

A further important advantage of the invention is that the mechanism is exceedingly simple not only in operation but also in installation, giving a high degree of rigidity and insuring positive action.

A still further important advantage of the invention is that it may be incorporated in tables wherein the top has its edges terminating flush with the table top skirt or apron, a style now in vogue. Furthermore, the use of the invention permits use of warp strips under the table top ends within the apron so that these strips may be concealed.

These and many other objects and advantages of convenience will become apparent to those versed in the art in the following description of one form of the invention, as illustrated in the accompanying drawings in which—

Fig. 1 is a top plan view of a table top in extended position with the invention applied thereto;

Fig. 2, a vertical transverse section on the line 2—2 in Fig. 1; and

Fig. 3, a similar section with the leaf raised and shifted to its usable position.

Like characters of reference indicate like parts throughout the several views in the drawings.

In the particular form of invention herein shown and described, the table top consists normally of the two end sections 10 and 11, both shiftably guided and retained by the usual slide generally designated by the numeral 12. These end sections 10 and 11 are supported in their extended and retracted positions by the top edges of the apron 13, the edges of the top sections terminating flush with the outside faces of the apron 13 when the top sections 10 and 11 are in their fully retracted positions.

As indicated in the drawings, but one slide 12 is employed and this slide extends longitudinally within the apron 13 to be secured and supported by the apron ends. Also it is to be noted that this slide 12 is located to one side of the center line of the table, being in the present showing at

approximately one-third of the distance between the sides of the apron 13. The top sections 10 and 11 are provided in the usual manner with stops 14 and 15 extending downwardly within the apron 13 to strike the ends of the apron 5 as a means of limiting the outward travel of the sections.

A pair of transversely positioned bars 16 and 17 are fixed in spaced apart relation between the sides of the apron 13 to be fixed thereto by their 10 ends and also to extend under and be fixed to the slide bar 12. These bars 16 and 17 are equally spaced from the transverse center line of the apron 13.

A leaf section 18 having a length exceeding 15 half of the transverse width of the apron 13 is linked and hinged from its underside toward each 20 end thereof to these bars 16 and 17 whereby the section 18 may be raised and lowered accompanied by endwise travel in parallel relation with the bars 16 and 17 as well as with the top sections 10 and 11. The width of the section 18 is selected to be that desired to create the desired 25 increase of table top length. In any event the width of this section 18 is slightly less than the 25 space between the inner ends of the top sections 10 and 11 when those sections are each shifted to their extreme outward positions as indicated in Fig. 1.

The hinge connections between the bars 16 and 30 17 and the leaf 18 must be sufficiently long so as to carry the leaf section 18 from its lower stored position, as indicated in Fig. 2, to the upper service position as indicated in Fig. 3. In the form herein shown, a very simple hinge connection is indicated.

A pair of generally U-shaped bars or wires 19 and 20 each have outturned feet bearing on the 35 respective bars 16 and 17 and retained there by any suitable means such as by the clips 21. The 40 central transverse bar between the legs of each of these hinged members bears against the underside of the leaf section 18 to be secured by like 45 clips 22 attached to the section 18. Since these 50 clips are mounted adjacent to the wire bends, end travel is prevented. These members 19 and 20 must be properly located to permit the leaf 18 to swing, as above indicated, from the lower position, Fig. 2, upwardly and outwardly to the 55 position shown in Fig. 3 where the outer end of the section 18 comes over and down on to the top edge of the apron 13.

A second leaf section 23 is hinged by its inner end to the inner end of the section 18. In the present form, two hinges 24 and 25 are employed 55

and are of a well known type commercially obtainable and will permit the section 23 to swing over and down on to the top side of section 18, as indicated in Fig. 2, and will also permit that 5 section 23 to be swung around away from the section 18 into the same plane therewith and bring the two ends of those sections into abutting contact so as to leave no gap therebetween. The length of this section 23 is made to be sufficient 10 to extend from the inner end of section 18 and terminate in the present instance, flush with the outer face of the side of the apron 13. The section 23 being hinged to and thereby carried directly by the section 18 lifts and lowers 15 directly therewith.

To operate the invention, assuming that the leaf sections 18 and 23 are initially in their stored positions as indicated in Fig. 2, the end sections 10 and 11 are pulled to their outer extreme positions so as to uncover the folded leaf. 20 Then the section 23 is grasped by its outer end 23a and lifted upwardly and carried around toward the dash line position as indicated in Fig. 3. In doing so, the underside of the section 23 25 adjacent its hinged end strikes the edge of the slide 12. This creates a fulcrum whereby continued pulling around of the section 23 lifts and pushes the section 18 upwardly and over and away from the slide 12. In fact after this section 23 travels from a vertical position, its weight 30 is sufficient to carry automatically the section 18 on up and over to its service position and the section 23 drops accordingly into its service position. The two end sections 10 and 11 are 35 then pushed respectively against the side edges of sections 18 and 23. Preferably interengaging dowel pins 30 are employed respectively along one edge each of the leaf sections 18 and 23 to enter in sockets provided in opposing top section 40 edges, all in the usual and customary manner so as to prevent accidental shifting or lifting of the leaf sections 18 and 23.

The foregoing operation places the table top in the extended or increased length position. 45 To restore the table top to its shortened position, the two end sections 10 and 11 are pulled outwardly to release the dowels 30. The short leaf section 23 is lifted by its outer end and swung upwardly and over past the vertical position, the underside of this section still fulcruming 50 over the slide 12, whereupon the section 18 is pulled inwardly and lowered as this section 23 is allowed to swing on over downwardly. It is to be noted that the combined thickness of the 55 leaf sections 18 and 23 together with the hinge attachments is less than the distance between the transverse bars 16 and 17 and the top edges of the apron 13 so that there will be suitable clearance to permit the end sections 10 and 11 60 to be pulled one toward the other over sections 18 and 23 when those sections are lowered to their stored positions resting on the bars 16 and 17.

65 Preferably a bearing plate 26 made out of metal is attached to the underside of the leaf section 23 adjacent its hinged end to bear against the slide member 12 so as to facilitate shifting thereover. Reference has been made to the slide 12 as the fulcrum for the member 23. 70 It is understood of course that the slide 12 may have a metal bar 27 extending from a side thereof of which is directly contacted by the plate 26. Although the slide construction may vary, the particular construction of the slide does not 75 enter into the invention. As indicated, warp

strips 28 and 29 may be applied to the under-sides of the top sections 10 and 11 inside of the apron 13 so as to be normally concealed therein and be utilized over the entire length of the top sections in order to prevent any tendency 5 of warping.

While we have herein shown and described our invention in the one particular form, it is obvious that structural changes may be employed without departing from the spirit of the 10 invention, and we therefore do not desire to be limited to that precise form beyond the limitations which may be imposed by the following claims.

We claim:

1. In a table top having a shiftable top section and an apron, the combination of a pair of leaf sections, means hinging inner ends of the leaf sections together, and hinge means comprising a plurality of links supported by said apron and connecting toward each end of one of the leaf sections to give a travel of the said one leaf section from below parallel with and to the level of said top section, said hinge means locating said one leaf section adjacent one side and within 25 said apron, and a fulcrum between the center line of the table and the apron and closer to the center line than to the apron, over which fulcrum the other of said leaf sections may be swung and bear to pull up and push over said one leaf 30 section from a stored position below said top section to a service position on said apron level with the top section.

2. In a table top structure having an apron and a shiftable top section, a leaf in two sections having one part hinged to the other on a transverse line to permit one part to fold over onto the other part for storage within said apron, a leaf support carried by said apron spaced below the top of the apron, link members interconnecting the 40 under leaf section with said support to secure travel of the leaf sections parallel with the leaf support, and a fulcrum between the center line of the table and the apron and closer to the center line than to the apron against which fulcrum 45 the over-folding leaf section is swung from the under leaf section to strike its underside thereagainst to exert a leverage tending to lift and shift the attached under-folding section.

3. In a table top structure having an apron and a shiftable top section, a leaf in two sections having one part hinged to the other on a transverse line to permit one part to fold over onto the other part for storage within said apron, a leaf support carried by said apron spaced below the top 55 of the apron, link members interconnecting the under leaf section with said support to secure travel of the leaf sections parallel with the leaf support, and a fulcrum between the center line of the table and the apron and closer to the center line than to the apron against which fulcrum 60 the over-folding leaf section is swung from the under leaf section to strike its underside thereagainst to exert a leverage tending to lift and shift the attached under-folding section, the 65 height of said fulcrum being such that, upon the leaf sections being unfolded into a common plane, the fulcrum will support and maintain the over-folded section in the plane common with said top section.

4. In a table top structure having an apron and a shiftable top section, a leaf in two sections having one part hinged to the other on a transverse line to permit one part to fold over onto the other part for storage within said apron, 75

15

35

45

50

55

60

65

70

75

5 a leaf support carried by said apron spaced below the top of the apron, link members interconnecting the under leaf section with said support, to secure travel of the leaf sections parallel with the leaf support, and a fulcrum between the center line of the table and the apron and closer to the center line than to the apron against which fulcrum the over-folding leaf section is 10 swung from the under leaf section to strike its underside thereagainst to exert a leverage tending to lift and shift the attached under-folding section, said fulcrum comprising a longitudinally disposed top section slide, said slide being disposed to that side of the table center line removed from said leaf sections when folded together.

5. In a table top construction having an apron

on each side and a table top section shiftable along the apron, a leaf in two sections foldable along a transverse line, a leaf support carried by said apron for holding the folded leaf in a stored position below said top section, links hinged 5 connecting and aligning the under-folding leaf section on said support and arranged and proportioned to move the section parallel with the support and guide the outer end of the under-folding leaf up over and onto said apron, and a fulcrum mounted adjacent the hinged ends of the leaf sections between the center line of the table and the apron and closer to the center line than to the apron to be in the path of the over-folding section when it is unfolded. 15
